UNITED STATES PATENT OFFICE.

JAMES M. GILCHREEST AND ELLIS F. GRAHAM, OF DENVER, COLORADO.

AUTOMOBILE-SIGNAL.

1,274,259.

Specification of Letters Patent. Patented July 30, 1918.

Application filed November 17, 1914. Serial No. 872,587.

To all whom it may concern:

Be it known that we, JAMES M. GILCHREEST and ELLIS F. GRAHAM, citizens of the United States, residing at the city and county of Denver and State of Colorado, have invented certain new and useful Improvements in Automobile-Signals; and we do declare the following to be a full, clear, and exact description of the invention, such as will enable others skilled in the art to which is appertains to make and use the same, reference being had to the accompanying drawings, and to the characters of reference marked thereon, which form a part of this specification.

Our invention relates to improvements in signals for automobiles, my object being to provide a simple attachment for improvements of this character, which will enable the chauffeur or person in charge of the machine, to notify other machines either approaching or following, that the machine in question is about to turn in one direction or the other. This is important, in order to avoid collisions. Heretofore, where no signal is employed, it is customary for the chauffeur to stick out his hand in order to indicate that he is about to turn. This is not a satisfactory signal as it is sometimes forgotten and on other occasions, it is not noticed by other machines in the vicinity, either for the reason that the display of the hand is of exceedingly short duration, or the other chauffeur or chauffeurs are not intently watching. Hence, it has been found of the utmost importance that a signal having the aforesaid function shall be attached to every machine of this character.

My improvement consists of a stationary and a pivoted bar, the latter carrying a small flag upon which any suitable words may be formed, or not, as may be desired. It is preferred that this flag shall be red in order to better attract attention. The stationary bar is secured to a stationary part of the machine, as the wind shield. The pivoted bar when the signal is not displayed, occupies an upright position parallel and in contact with the stationary bar. When it is desired to display the signal, the upper extremity of the pivoted bar is given a slight outward movement by the hand of the chauffeur. A stop is mounted upon a flexi-

ble device, as a cord or wire, which passes through the upper extremity of the stationary bar and is connected with the outer extremity of the pivoted bar, the stop adapted to engage the stationary bar and limit the downward movement of the pivoted bar. When it is desired to raise the signal to the non-signaling position, the chauffeur grasps this stop, which is in the form of a ball of sufficient size for the purpose, and pulls the pivoted bar and its flag upwardly to its normal position.

Having briefly outlined our improved construction we will proceed to describe the same in detail, reference being made to the accompanying drawing, in which is illustrated an embodiment thereof. In this drawing,

Figure 1 is a view of the wind shield of an automobile with two of our improved signals applied, one on either side. This is a view looking from a position in the machine, forwardly or in the direction of travel, toward the wind shield.

Fig. 2 is an end view or a view looking in the direction of arrow 2, Fig. 1, the pivoted-angle-carrying-bar being shown in the signal displaying position by full lines, and in the normal position by dotted lines, the parts being shown on a larger scale.

Fig. 3 is a view looking in the direction of arrow 3, Fig. 2, the parts being shown on the same scale as in Fig. 2. This view of the displayed signal is taken in a direction opposite the signal at the left in Fig. 1.

Fig. 4 is a cross section taken on the line 4—4, Fig. 2, looking downwardly, the parts being shown on a larger scale.

The same reference characters indicate the same parts in all the views.

Let the numeral 5 designate an upright bar to which is secured a pair of spring clamps 6 by means of screws 7. These clamps are provided with projections 8 and 8^a, which extend from the circular part 9 of the clamp. The screws 7 are passed through the projections 8 close to the part 9 of the clamp, whereby the bar 5 is close to the part 9. The projection 8 is of sufficient length to extend far enough beyond the bar 5 to allow the coöperating signal-carrying-bar 10 to assume a position close to the bar 5 and in contact with the pro-

jection, which forms a stop to prevent the bar 10 from moving beyond its normal or upright position when the signal is raised from the danger to the safe position. The 5 clamping parts 9 are applied to an upright stationary bar 12 which may be one of the regular upright arms of the wind shield, or the wind shield may be equipped with an auxiliary or reinforcing U-shaped bar for 10 the purpose (see Fig. 1). As illustrated in the drawing, the parts 9 of the clamps which surround the stationary member 12, are provided with ears 13 to which are secured small bolts 14 to which nuts 15 are 15 applied. In this manner, the clamps are secured to the stationary member 12, the signal being then attached to the machine in operative relation. It is preferred to employ one of these signals on each side of the 20 machine, but as the signals are substantially identical in construction, the description of one is sufficient for both.

The bar 10 has one extremity pivoted, as shown at 16, to the lower extremity of the 25 bar 5, and to the bar 10 is secured a flexible signaling device, as a flag 17, which may have any desired words thereon to indicate its use; or the flag may be devoid of words, in which event, its color, (being red), indicates to other machines or pedestrians in the vicinity, that the machine to which the signal is attached, is about to turn in the direction of the side where the signal is displayed. In the drawing, the words "Safety 30 to the left," are shown on the flag element of the signal, but this is not necessary, as above indicated. It is evident that other words, if desired, may be substituted for those shown, these words as indicated in 35 the drawing being simply an illustration of the idea that words of any suitable character and conveying the desired information may be used to supplement the performance of the signaling function. The flag 17 is secured to the bar 10 by suitable fastening devices as screws 18. To the extremity of the bar 10 remote from the pivot 16, is secured, as shown at 19, one extremity of a cord, wire or small cable 20, which passes 40 through a perforation 21 formed in the upper extremity of the relatively stationary bar 5, an antifrictional roller or pulley 22 being employed and mounted in the bar just below the perforation, so that the flexible 45 device 20 will engage the antifrictional device while passing through the perforation. The length of the cord or flexible device 20 is such that when the signal is displayed the bar 10 will be held in a position at right 50 angles or approximately at right angles to the bar 5, and to this end the cord 20 is equipped at its free extremity with a stop in the form of a ball 23, which is too large 55 to pass through the perforation 21, and con-

sequently, forms a stop to prevent the signal arm 10 from moving downwardly farther than is necessary, or farther than its position perpendicular to the bar 5.

The bar 10 is slightly longer than the bar 5, so that when the bar 10 is in the upright 70 position, it projects a short distance above the top of the bar 5, as indicated by dotted lines in Figs. 2 and 3. This makes it practicable for the chauffeur to strike the upper extremity of the bar 10 for the purpose of 75 throwing the signal down to the signaling position, and thus causing the flag to assume the danger position, the ball 23 preventing the flag from moving farther downwardly than is necessary, as heretofore explained. 80

From the foregoing description, the use and operation of our improved signal will be readily understood. The automobile is equipped with two of these signals, one on each side, as illustrated in Fig. 1 of the 85 drawing. The bar 5, which is attached to the clamps 9, as heretofore stated, is placed in an upright position adjacent one of the upright arms or side bars of the wind shield, as that designated by the numeral 12, and the parts 9 of the clamps 6 applied thereto by the use of the screws 14 and the nuts 15. Normally, the flag or signal member 17 is in the raised position as shown at the right of Fig. 1. When it is desired to indicate that 90 the driver of the machine is about to turn to the right or left, the chauffeur reaches up with his hand and strikes the upper exposed extremity of the bar 10, in a direction to cause this extremity to move downwardly 95 and outwardly, whereby the flag is displayed, or thrown to the danger position on the side toward which the chauffeur intends to turn. After the turn has been made, the chauffeur grasps the ball 23 and raises the 100 signal to the normal or safe position.

Attention is called to the fact that our improved signal may be employed in connection with vehicles other than automobiles, and with equal advantage whenever or wherever it may be necessary or desirable so to do. 110

Having thus described our invention, what we claim is,—

An automobile signal adapted to be secured to the wind shield of an automobile, 115 said signal comprising a bar having a perforation in its upper extremity and secured to the said shield in an upright position, a second bar pivoted at one extremity and adapted to occupy an upright position in co-operative proximity to the stationary bar, a flexible flag mounted upon said second bar, a flexible device connected with the free extremity of the second bar and passing through the perforation in the upper extremity of the first bar, permitting the second bar to swing about its pivot to a position at right angles to the first bar and at 120 125 130 135 140 145 150

right angles to the direction of travel of the automobile, and means mounted upon the flexible device and adapted to engage said first bar adjacent the perforation to maintain the second bar at the position perpendicular to the first bar substantially as described.

In testimony whereof we affix our signatures in presence of two witnesses.

JAMES M. GILCHREEST.
ELLIS F. GRAHAM.
